HIS ATTORNEY'S

UNITED STATES PATENT OFFICE.

FRED C. MORRISON, OF CHICAGO, ILLINOIS.

COMBINED LAUNDRY-REGISTER AND MATCH-SAFE.

SPECIFICATION forming part of Letters Patent No. 554,712, dated February 18, 1896.

Application filed April 19, 1895. Serial No. 546,367. (No model.)

To all whom it may concern:

Be it known that I, FRED C. MORRISON, a citizen of the United States, residing in Chicago, in the county of Cook and State of Illinois, have invented a new and useful Improvement in Pocket Laundry-Registers, of which the following is a specification.

My invention relates to pocket-registers.

The object of my invention is to provide a pocket laundry-register of a simple, compact, and neat construction capable of being made at small cost from sheet metal by punches and dies, and by use of which persons can conveniently keep a full and reliable record of the articles which they send weekly to public laundries, thereby detecting any mistake or shortage that may exist when the articles are returned.

A further object of my improvement is to so construct the device that it may be made a part of or combined with any suitable object customarily carried in the pocket—such, for example, as a match-safe, a toothpick-case, a stamp-case, a pocket-book, or other like article.

My invention consists, in connection with a pair of inclosing plates, of a series of toothed counter-wheels furnished with numerals on their face and journaled upon one of the plates, a toothed holding-bar adapted to be moved into and out of engagement with the teeth of the counter-wheels to hold the wheels normally in position, and a reciprocating locking-bar for locking the toothed holding-bar in engagement with the counter-wheels, the locking-bar and the toothed holding-bar being between the inclosing plates and held in position thereby.

It further consists, in connection with the inclosing plates, of the counter-wheels arranged in two rows and a pair of toothed holding-bars, one adapted to engage the wheels of one row and the other the wheels of the other row, and a single or common locking-bar having two sets of cams for engaging the cams of the holding-bars, the locking-bar being between the two holding-bars.

It further consists in the novel construction of parts and devices, and in the novel combinations of parts and devices herein shown and described, and specified in the claims.

In the accompanying drawings, forming a part of this specification, Figure 1 is a front side elevation of a device embodying my invention. Fig. 2 is an edge view. Fig. 3 is a section on line 3 3 of Fig. 2. Fig. 4 is a section on line 4 4 of Fig. 2. Fig. 5 is a section on line 5 5 of Fig. 1. Fig. 6 is a section on line 6 6 of Fig. 1. Fig. 7 is a section on line 7 7 of Fig. 3. The arrows indicate the directions in which the several sectional views look. Fig. 8 is a bottom view. Fig. 9 is a detail perspective view of the reciprocating locking bar or slide, the same showing a slight spring or curvature given to this slide, so that the tension of the spring will cause sufficient friction of the slide against the inclosing plates to cause the slide to remain in whatever position it may be placed. Fig. 10 is an enlarged view similar to Fig. 6, with the match-safe spring omitted. Fig. 11 is a detail perspective of the plate to which the wheels are pivoted, and Fig. 12 shows a modification in which the match-safe is omitted.

In the drawings the same parts are indicated by the same letters of reference in all the figures.

Referring to the drawings, A and B represent the inclosing plates, C an end plate between the inclosing plates, and D the counter-wheels arranged in two rows D' D' between the inclosing plates A and B and journaled to one of said plates, B, by suitable pivots d, preferably made integral with the wheels D by stamping a hub or boss or projection thereon. The counter-wheels D are each furnished with suitable teeth d', which engage corresponding teeth f on the movable holding-bars F F. The holding-bars F F are furnished with cam projections f' f', which engage corresponding cam projections g g on the reciprocating locking-bar G. The locking-bar G has a lip g' turned up at its end and projecting through a slot a in the inclosing plate A to serve as a thumb-piece for moving the locking-bar and also as a guide for the same, and the locking-bar G has a similar lip g² at its other end fitting in a slot b' in the plate B to serve as a guide for this end of the sliding locking-bar. The plate B, to which the counter-wheels D are pivoted by their hubs d fitting in the holes b², is furnished with a marginal flange b³ at one end, against which

the holding-bars F F abut at one end, and the end plate C serves as an abutment at the other end of the holding-bars F F to keep them in place longitudinally. The plate B is also preferably provided with flanges B' B' at its side edges fitting in and forming part of the match-safe case A', which is made integral with the plate A. The plate A is provided with arc-shaped recesses or openings 10 a', one for each counter-wheel D, to give ready access thereto, and thus enable each wheel to be turned by the finger or nail when desired. The plate A is further furnished with a series of index or indicator openings 15 a'', one for each counter-wheel, registering with the circle d'', in which the numerals d''' are arranged on each of the counter-wheels.

In applying my invention to a match-safe, as illustrated in the drawings at Figs. 1 to 11, 20 I preferably make the inclosing plate A integral with the outer shell A' of the match-safe, the same being drawn up, as usual, out of one piece of sheet metal, and the end plate C interposed between the inclosing plates A B is made integral with the band C', usually placed at the mouth of the metal match-safe shell to form a guide or stop for the hinged cover H of the match safe or case. The cover H is hinged at h to the shell A' and is automatically 25 opened by a U-shaped spring K fitting inside the match-receptacle A'', having a bent end or lip k fitting against the cover H just above its spring h. The opposite end k' of the spring engages a catch h' on the cover, so that the 30 same spring serves also to hold the cover closed, the end of the spring being furnished with a recess or catch k'' engaging the corresponding catch h' on the cover H. To release the catch which holds the cover closed, the 35 spring is furnished with a button k''' projecting through a hole a''' in the case A'.

In the modification illustrated in Fig. 12 the match-safe is omitted, and the plate A is furnished with a marginal flange a'' at its sides 40 and ends to better inclose the wheels D and keep the plates slightly farther apart than the thickness of the counter-wheels, so that they may be readily turned. The dotted lines in this figure indicate projections a'', with which 45 the plate A may be provided for securing the same to a pocket-book or other article.

Small springs f'' may be placed between the wheels D and the toothed holding-bars F to throw the holding-bars out of engagement 50 with the wheels D when the locking-bar G is withdrawn; but ordinarily these springs will not be necessary, as the wedging or cam action of the teeth on the wheel and on the locking-bar will cause the locking-bar to readily 55 move out of the way when attempt is made to turn one of the wheels D after unlocking the slide G.

The locking-bar is slightly curved, so that 60 its spring action will serve to hold it normally in place and prevent accidental unlocking of the same.

The plates A B' are secured together by rivets a'.

I claim—

1. A pocket laundry register and indicator, 70 consisting in the combination of inclosing plates with a series of counter-wheels, furnished each with a circle of numerals, between them, and provided with teeth, a movable toothed holding-bar engaging the teeth 75 of said wheels, and a movable locking-bar for locking the toothed holding-bar in engagement with said counter-wheels, substantially as specified.

2. A pocket laundry register and indicator, 80 consisting in the combination of inclosing plates with a series of counter-wheels, furnished each with a circle of numerals, between them, and provided with teeth, a movable toothed holding-bar engaging the teeth 85 of said wheels, and a movable locking-bar for locking the toothed holding-bar in engagement with said counter-wheels, said holding and locking bars being furnished with cam projections, substantially as specified. 90

3. The combination with inclosing plates, of a series of toothed counter-wheels arranged in two rows and journaled on one of said plates, a pair of movable toothed holding-bars engaging said counter-wheels, and a locking-bar 95 between the holding-bars, said holding and locking bars and said counter-wheels being all inclosed between said plates, substantially as specified.

4. The combination with inclosing plates, of 100 a series of toothed counter-wheels arranged in two rows and journaled on one of said plates, a pair of movable toothed holding-bars engaging said counter-wheels, and a locking-bar 105 between the holding-bars, said holding and locking bars and said counter-wheels being all inclosed between said plates, said holding and locking bars being provided with cams, substantially as specified.

5. The combination with inclosing plates, of 110 a series of toothed counter-wheels arranged in two rows and journaled on one of said plates, a pair of movable toothed holding-bars engaging said counter-wheels, and a locking-bar 115 between the holding-bars, said holding and locking bars and said counter-wheels being all inclosed between said plates, said holding and locking bars being provided with cams, and said locking-bars being furnished with a lip, and one of said plates having a slot 120 through which the lip on the locking-bar projects, substantially as specified.

6. The combination with two inclosing plates of a series of toothed counter-wheels furnished with integral hubs or pivots, 125 inclosed between and held in position by said plates, said integral hubs or pivots entering holes for bearings in one of said plates, a toothed holding-bar and a movable locking-bar engaging the holding-bar and locking it 130 positively in engagement with said counter-wheels, substantially as specified.

7. The combination with two inclosing plates of a series of toothed counter-wheels furnished with integral hubs or pivots, inclosed between and held in position by said plates, said integral hubs or pivots entering holes for bearings in one of said plates, a toothed holding-bar and a locking-bar, one of said plates having a series of index-openings one for each of said counter-wheels, and said locking-bar having projecting lips at its ends and said plates being provided with slots to receive the lips on the locking-bar, substantially as specified.

8. The combination with a pair of inclosing plates of a series of toothed counter-wheels, a toothed holding-bar, and a movable locking-bar engaging the holding-bar and locking it positively in engagement with said counter-wheels, substantially as specified.

9. The combination with a pair of inclosing plates of a series of toothed counter-wheels, a toothed holding-bar, and a curved spring-acting movable locking-bar engaging the holding-bar and locking it positively in engagement with said counter-wheels, substantially as specified.

10. The combination with a pair of inclosing plates of a series of toothed counter-wheels, a toothed holding-bar, a movable locking-bar engaging the holding-bar and locking it positively in engagement with said counter-wheels, and a match-safe case integral with one of said plates, provided with a hinged cover and having a U-shaped spring bearing at one end against the hinged cover to open the same, and engaging at the other end a catch on the cover to hold the same closed, substantially as specified.

11. The combination with a pair of inclosing plates A B with end plate C, a series of toothed counter-wheels D arranged in two rows, a pair of toothed holding-bars F F, a locking-bar G provided with cams and a projecting lip, one of said plates having index-openings for each of said counter-wheels, and a slot to receive the lip of the locking-bar, substantially as specified.

12. The combination with a pair of inclosing plates of a series of toothed counter-wheels, a toothed holding-bar, a locking-bar, and an end plate, one of said inclosing plates having a flange b³ at one end, substantially as specified.

13. The combination with a match-case shell A A', furnished with a series of index-openings a² in one of its sides, of a plate B having flanges B' B' fitting inside said shell and provided with a series of holes b² and a series of counter-wheels D inclosed between said plate B and the side A of said shell, said shell having recesses a' to give access to said counter-wheels, substantially as specified.

14. The combination with a match-case shell A A', furnished with a series of index-openings a² in one of its sides, of a plate B 65 having flanges B' B' fitting inside said shell and provided with a series of holes b² and a series of counter-wheels D inclosed between said plate B and the side A of said shell, said shell having recesses a' to give access to said 70 counter-wheels, said counter-wheels having integral hubs d serving as the pivots of said wheels, substantially as specified.

15. The combination with a match-case shell A A', furnished with a series of index-openings a² in one of its sides, of a plate B 75 having flanges B' B' fitting inside said shell and provided with a series of holes b² and a series of counter-wheels D inclosed between said plates B and the side A of said shell, said shell having recesses a' to give access to said counter-wheels, said counter-wheels having integral hubs d serving as the pivots of said 80 wheels, and a bent plate C serving as an end plate to inclose the counter-wheels and as a 85 seat for the cover of the match-safe, substantially as specified.

16. The combination with a match-case shell A A', furnished with a series of index-openings a² in one of its sides, of a plate B 90 having flanges B' B' fitting inside said shell and provided with a series of holes b² and a series of toothed counter-wheels D inclosed between said plates B and the side A of said shell, said shell having recesses a' to give access to 95 said counter-wheels, said counter-wheels having integral hubs d serving as the pivots of said wheels, a bent plate C serving as one end plate to inclose the counter-wheels and as a seat for the cover of the match-safe, a 100 toothed holding-bar and a locking-bar, substantially as specified.

17. The combination with a match-case shell A A', furnished with a series of index-openings a² in one of its sides, of a plate B 105 having flanges B' B' fitting inside said shell and provided with a series of holes b² and a series of toothed counter-wheels D inclosed between said plate B and the side A of the shell, said shell having recesses a' to give access to 110 said counter-wheels, said counter-wheels having integral hubs d, a bent plate C serving as one end plate to inclose the counter-wheels and as a seat for the cover of the match-safe, a toothed holding-bar and a locking-bar, a hinged cover H and a spring K bearing against the cover at one end and furnished with a catch engaging the cover at the other end, substantially as specified.

FRED C. MORRISON.
